UNITED STATES PATENT OFFICE.

HUGH STEWART, OF FORT WAYNE, INDIANA.

WINDOW-CLEANER.

SPECIFICATION forming part of Letters Patent No. 616,504, dated December 27, 1898.

Application filed August 11, 1898. Serial No. 688,378. (No model.)

To all whom it may concern:

Be it known that I, HUGH STEWART, a citizen of the United States, residing at Fort Wayne, in the county of Allen and State of Indiana, have invented certain new and useful Improvements in Cleaners for Windows, &c.; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to improvements in devices for cleaning windows, floors, and other surfaces, and has for its object the production of an efficient device of this character possessing advantages in point of simplicity of construction and durability.

The invention consists of the construction and relative arrangement of parts composing the improved cleaning device, all of which is hereinafter fully and clearly described, and specifically set forth in the concluding claims.

In the accompanying drawings, forming a part of this specification, Figure 1 is a perspective view of the cleaning device. Fig. 2 is a bottom plan view, partly broken away. Fig. 3 is a longitudinal sectional view on line 3-3 of Fig. 2, and Fig. 4 is a cross-sectional view on line 4-4 of Fig. 3.

Referring to the said drawings by letter, A denotes a casing, preferably of triangular form in cross-section and constituting a reservoir for water, which is supplied through the opening controlled by the closure b. The casing is attached to a handle c through the medium of a ferrule c', and to strengthen such attachment the ferrule is passed through both of the side walls of the casing and secured by soldering or otherwise, as shown more clearly in Fig. 4.

In the bottom a of the casing are a plurality of fine openings a' a'', through which the water is discharged, said openings being preferably formed by punching in a manner to bring the roughened edges of the openings undermost, for a purpose presently to be explained. The openings occupy the central portion of the casing-bottom for its entire length, and between this central portion and

the edges are longitudinal grooves a² a³. The cloth or mop d is placed over the casing-bottom and is secured in position by means of rods e e, which are pivotally attached to one end of the casing at e' in alignment with the grooves a², whereby said rods, when in securing position, force the cloth or mop into the grooves and effectually hold it in place. The rods e at their other end are provided with locking means in the nature of a pivoted hasp e², which has at its outer end a rounded shoulder e³, adapted to engage a similar shoulder a³ at the top of the casing. The rods are of spring metal, and a slight upward pressure at their outer end enables the ready engagement or disengagement of the hasp. In addition to the means described for securing the cloth or mop in place are the roughened edges of the openings a', which penetrate the fabric and thereby preclude displacement of the latter.

At the side of the casing opposite the handle and near the lower casing edge are two flanges f f', between which is removably placed a strip g, of rubber or other suitable material, said strip serving as the means for wiping the washed window or other surface. The flanges f f' are preferably formed by bending a strip of sheet metal to U form, and the flange f is braced by the additional bend f'', which is soldered at its lower end to the casing side.

In the operation of the invention the cloth or mop is secured in place and the reservoir filled with water. The device is then manipulated to wash the surface to be cleaned, and whether such surface be in a vertical or a horizontal plane the casing-bottom will be so disposed as to allow of water passing through the openings and percolating through the cloth or mop-body. In this way throughout the entire washing operation clean water is constantly supplied, and should the contents of the reservoir become exhausted the latter may be easily refilled without disturbing the cloth.

The peculiar form of the casing permits of the device being used to effectually clean corners and other portions of surfaces heretofore inaccessible to appliances of this character, and owing to the number and location of water-discharge openings the cloth or mop

is evenly saturated and the efficiency of the device thereby greatly enhanced.

In using the wiper *g* the device must be inverted, the result being that the perforated bottom is brought uppermost and the water in the reservoir is prevented from flowing therefrom, as will be understood.

My improved cleaning device is very simple in construction. Hence it may be cheaply made. Moreover, the parts being few in number there is no liability to disorder.

I claim as my invention—

1. A cleaning device comprising a reservoir-casing provided throughout its bottom with fine perforations, and provided with longitudinal grooves at the sides of the perforated portion, a cloth or mop, spring-rods pivoted at one end to an end of the casing and adapted to force the cloth or mop into said grooves, a hasp pivoted to the other end of the rods and provided at its upper end with a shoulder adapted to engage a shoulder on the casing-top, and a handle-ferrule passed through and secured at both sides of the casing, substantially as described.

2. A cleaning device comprising a reservoir-casing of substantially triangular form in cross-section provided throughout its bottom with fine perforations having roughened edges presented outwardly, and provided with longitudinal grooves at the sides of the perforated portion, a cloth or mop, spring-rods pivoted at one end to an end of the casing and adapted to force the cloth or mop into the grooves and into engagement with the roughened edges of the perforations, a hasp pivoted to the other end of the rods and provided with a shoulder adapted to engage a shoulder on the casing-top, flanges at one side of the casing near its lower end, one of the flanges being braced, and a rubber or other wiper between the flanges, substantially as described.

In testimony whereof I affix my signature in presence of two witnesses.

HUGH STEWART.
